CLAIM

The ornamental design for a spray head, as shown and described.

DESCRIPTION

FIG. 1 is a perspective view of a spray head showing my new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a perspective view thereof wherein the nozzle has been rotated 180°.

The bottom view of the spray head is not visible during ordinary use and forms no part of the claimed design.
